UNITED STATES PATENT OFFICE.

GEORGE E. FREY, OF STEUBENVILLE, OHIO.

CAR-FENDER.

1,235,307.

Specification of Letters Patent. Patented July 31, 1917.

Application filed May 11, 1917. Serial No. 167,906.

To all whom it may concern:

Be it known that I, GEORGE E. FREY, a citizen of the United States of America, and resident of Steubenville, county of Jefferson, and State of Ohio, have invented 5 certain new and useful Improvements in Car-Fenders, of which the following is a specification.

This invention relates broadly to fenders 10 for wheeled vehicles, and it has for its primary object to provide a simple and comparatively inexpensive fender for cars and the like adapted to be actuated by impact with an object or person in the trackway 15 to assume a position affording a receptacle into which such object or person may fall and be carried without liability to serious injury.

A further object is to provide a safety 20 fender of the character mentioned which may be folded to occupy a substantially upright out-of-the-way position when occasion demands, as when it is desired to couple other cars thereto, or to employ the 25 car as a trailer.

With these and other objects in view, the 30 invention resides in the features of construction, arrangement of parts and combinations of elements which will herein- 35 after be fully described, reference being had to the accompanying drawings, in which—

Figure 1 is a top plan view of the invention;

Fig. 2 is a side elevation of the same in 35 working position;

Fig. 3 is a similar elevation in tripped 40 position;

Fig. 4 is an enlarged detail view in side 45 elevation illustrating the means whereby the tripping movement is limited;

Fig. 5 is a section on line 5—5, Fig. 4; and—

Fig. 6 is an enlarged plan view of a fragment 45 of the netting.

Referring to said drawings, in which like designating characters distinguish like parts throughout the several views—

1 indicates the opposite parallel side mem- 50 bers of a main fender frame, the rear ends of which are designed to be rigidly mounted upon a suitable part, as the sills, of a car. Pivotaly mounted upon pivot bolts 2 car-

ried by said side members 1 at points located a suitable distance rearward of the 55 front ends of the latter are the rear end portions 3 of the side members 4 of a tilting catch-frame which is of substantially rectangular form and which is preferably composed of a single length of metal tubing 60 flattened at its ends to form said end portions 3.

Rigidly mounted upon the side members 1 at a suitable distance rearward of their 65 front ends are the lower ends of upright posts or supports 5 which are connected at their upper ends by a transverse bar 6, said posts and bar being preferably formed of a single length of metal tubing, as shown. Connected at one end to said transverse bar 70 6 is a netting 7 which has its opposite end connected to the transverse member 8 of the catch-frame. Said netting may be composed of any appropriate flexible material or fabric, that herein shown being composed of 75 a plurality of longitudinally extending link chains 7^a and a plurality of transversely extending cross-chains 7^b interlinked with said chains 7^a.

Located close inside the confines of the 80 main-frame and the catch-frame at each side is a long retractile coil spring 9 which has its front end attached to a suitable hook or eye-bolt, as 10, carried by the side member 4 adjacent to the front end of the catch-frame, 85 and has its rear end attached to a similar hook or eye-bolt 11 carried by the frame member 1 at a suitable distance rearward of the adjacent pivot-bolt 2.

The netting 7 serves to support the front 90 end of the catch-frame and has a length which permits said frame to assume a normal, or running, position wherein it is inclined downward slightly with respect to the plane in which the pivot-bolts 2 and the 95 eye-bolts 11 are located, as shown in Fig. 2. Due to said inclination of the catch-frame the springs 9 serve to yieldingly resist elevating movement of said frame from running position. When, however, the said 100 frame is tripped or actuated, as by the weight of a person or object falling upon the netting, to swing to an upwardly inclined position, as shown in Fig. 3, said springs serve to yieldingly maintain said 105 frame in the last-mentioned position. In

such position of the catch-frame the flexible netting affords a bag-like receptacle wherein the person or object by which the fender has been tripped is supported and prevented 5 from falling off.

For limiting the extent of the upward swinging movement of the catch-frame when the latter is tripped as aforesaid, and thus to prevent undue injury to a person received 10 upon the fender, a stop 12 is provided on each of the side members 1 at or adjacent to the forward end of the latter, said stop preferably comprising an upwardly extending arm bolted to the side-member and having 15 an inturned, or laterally disposed, lug 12^a adapted to have the portion 3 of the adjacent side member 4 seat thereagainst, as shown in Figs. 3, 4 and 5. Said stop 12 is mounted upon a pair of bolts 13 which 20 have coil springs 14 interposed between the outer face of the adjacent member 1 and washers 15 seated against the bolt heads, as shown in Fig. 5. Said springs 14 normally serve to yieldingly support said stops in 25 close seating relation to the members 1. When, however, it is desired to swing the catch-frame back to inoperative position against the transverse bar 6, as when it is desired to couple the car to another, the 30 stops 12 may obviously be swung back against the tension of their seating springs 14 to withdraw their lugs 12^a from the path of movement of said frame.

What is claimed is—

35 1. A car fender comprising opposite main-frame members, upright supports mounted upon said members rearward of the front ends of the latter, a transverse bar carried by said supports, a catch-frame pivotally mounted on said main-frame members and extending forward therefrom, a flexible netting connected at one end to said transverse member and at its opposite end to said catch-frame, and retractile coil springs interposed 40 between said frames in such manner that they are placed under their maximum tension when said frames are in alinement and which are adapted to yieldingly maintain said catch-frame either in a downwardly inclined position or in an upwardly inclined 45 position.

50 2. A car fender comprising a pivoted catch-frame normally supported in an extended position wherein it has a slight downward inclination and adapted for movement to an upwardly inclined position, a netting having its forward end connected to the front end of said frame, and retractile coil springs having their rear ends attached to a fixed part and their front ends attached 55 to said frame adjacent to the front end of the latter, said springs tending to yieldingly maintain said frame at either of its limits of movement.

3. A car fender comprising a fixed portion, a catch-frame pivoted at its rear end upon said fixed portion and movable between limits located above and below the horizontal plane in which its pivots are located, retractile coil springs connected at their front 65 ends to said catch-frame and at their rear ends to fixed parts located rearward of said pivots, said springs being under greatest tension when said catch-frame occupies a position between said limits, said springs being adapted to yieldingly maintain said frame at either of said limits of movement, and a netting having its rear end supported above and rearward with respect to said pivots and having its front end connected to 70 the front end of said frame.

4. A car fender comprising a fixed portion, a catch-frame pivoted at its rear end upon said fixed portion and movable between limits located above and below the horizontal plane in which its pivots are located, retractile coil springs connected at their front 75 ends to said catch-frame and at their rear ends to fixed parts located rearward of said pivots, said springs being adapted to yieldingly maintain said frame at either of said limits of movement, and a netting having its rear end supported above and rearward with respect to said pivots and having its front end connected to the front end of said frame, said netting serving to support the front end of said frame at its lower limit of 80 movement.

5. A car fender comprising a fixed portion, a catch-frame pivoted at its rear end 85 upon said fixed portion and movable between limits located above and below the horizontal plane in which its pivots are located, retractile coil springs connected at their front ends to said catch-frame and at their rear ends to fixed parts located rearward of said pivots, said springs being adapted to yieldingly maintain said frame at either of said limits of movement, a netting having its rear end supported above and rearward with respect to said pivots and having its front end connected to the front end of said frame, said netting serving to support the front end of 90 said frame at its lower limit of movement, and means adapted to be engaged by said frame limiting the extent of upward movement of the latter.

6. A car fender comprising a fixed portion, a catch-frame pivoted at its rear end 95 upon said fixed portion and movable between limits located above and below the horizontal plane in which its pivots are located, retractile coil springs connected at their front ends to said catch-frame and at their rear ends to fixed parts located rearward of said pivots, said springs being adapted to yieldingly maintain said frame at either of said limits of movement, a netting having its rear end 100

supported above and rearward with respect to said pivots and having its front end connected to the front end of said frame, said netting serving to support the front end of 5 said frame at its lower limit of movement, and means adapted to be engaged by said frame limiting the extent of upward movement of the latter, said means being with-

drawable from the path of movement of said frame. 10

In testimony whereof, I affix my signature in presence of two subscribing witnesses.

GEORGE E. FREY.
